INTENSIFIER HIGH PRESSURE VALVE AND BLOCK ASSEMBLY

Rae A. Prosser, South Charleston, and John W. Luchsinger, Charleston, W. Va., assignors to Union Carbide Corporation, a corporation of New York

Filed Nov. 13, 1961, Ser. No. 151,697
2 Claims. (Cl. 103—228)

The present invention relates to an improved fluid system valve and more particularly to a high pressure valve ideally suited for use in intensifier systems wherein fluids are raised from low suction or intake pressures in the order of about 2000 p.s.i.g. to relatively high discharge pressures in the order of 35,000 p.s.i.g. and above, by means of reciprocating piston and plunger type pumps and intensifiers. Apparatus according to the present invention permits size reduction of parts subjected to discharge pressures over known devices for such use and provides for mitigation of cyclic fatigue loading normally encountered in known valves adapted for high pressure applications.

Valves suitable for high pressure cyclic pumping operations at discharge pressures in the order of 35,000 p.s.i.g. and upward are known in the valve art to be prone to material fatigue failures due to the continual application and relaxation of pressure loads especially against sharp edges and corners in the valve interior passages where stress concentrations occur. Present efforts directed towards mitigation of these fatigue failures in high pressure valves are addressed generally to reducing the severity of stress concentrations, where such are known to occur, by rounding off sharp edges and filleting sharp corners at valve passage intersections and transition points. It has been found, however, that while rounding off and filleting techniques reduce stress concentrations to some extent, these techniques have not effected reduction of stresses to the order of stress levels obtaining in straight sections of the valve passages.

In conventional low pressure compressor equipment operating at below about 35,000 p.s.i.g., stress concentration problems and related fatigue failures are mitigated by the use of components having sufficient structural strength to withstand maximum stresses encountered. In high pressure equipment, however, components of sufficient structural strength to withstand expected fatigue stresses at high stress concentration points would have to be made unusually massive and necessarily cumbersome. Practical considerations frequently militate against or even prevent such a solution to this problem.

The present invention provides a valve uniquely suitable for high pressure fluid pumping which, in operation, produces no excessive stress concentrations from cyclic loading. The valve of this invention operates successfully and continuously without failure or repair for periods longer than those experienced with known high pressure valves at discharge pressures above 35,000 p.s.i.g.

Apparatus according to the present invention comprehends an annular suction, center discharge type high pressure valve assembly in a valve block designed so that on a pump piston or plunger suction stroke fluid flows into an annular space and through a sufficient number of holes connecting to a concentric groove covered by a suction valve disc and then into a pump cylinder; and on the discharge stroke, the fluid is forced through a hole in the center of the suction valve disc through a center discharge passage located through the center of the valve block, through a poppet valve and out into the discharge line. With this design, a minimum number of stress raisers are present and such common stress raisers as

2

are found in intersecting bores in a reciprocating cylinder are eliminated. In addition, the main valve block body is protected from discharge pressure and is subjected only to suction pressure of the pumped fluid. Fatigue cracking of these valves and valve block parts which has been a problem is thereby minimized.

With the foregoing and other features in view, which shall more fully hereinafter appear, the present invention comprises novel constructions, combinations and arrangements of components as will now be described in detail and as recited in the appended claims and illustrated in the accompanying drawing, which is a sectional view through a valve according to our invention, showing internal passages and components thereof.

Referring to the drawing, a valve body portion 17, is shown affixed to a pump 11, which includes a reciprocating piston 13. A discharge passage 19 extends through a group of core block members 49, 51, 53 and 55 disposed interiorly of body portion 17. Precise details according to which the discharge passage and its radially enlarged sections and the other passages discussed here are formed and disposed in the core block members, as well as more complete descriptions of the several core block members themselves, are set forth hereinafter. Discharge passage 19 connects a port 15 of pump 11 to a fluid outlet 21. A first longitudinally extending radially enlarged section 23 in discharge passage 19 is located adjacent the port 15 of pump 11 and connects thereto through a hole in a facia block 55. A second longitudinally extending radially enlarged section 25 in discharge passage 19 is located interior of the valve body portion 17 in a thrust block 49. An annular recess 27, formed by recessed peripheral edges on the thrust block 49 and a first follower block 51, transversely surrounds bore 19 and is located in a longitudinally displaced position in the valve body portion 17 with respect to first radially enlarged section 23 of the discharge passage 19. A multiplicity of suction passages 29 connects annular recess 27 with first radially enlarged section 23 of discharge passage 19 and an intake passage 31 connects annular recess 27 with a fluid inlet 33 at a point on the body portion exterior. An inlet valve member 35, in the form of an annular disc having a centrally located opening 37 therethrough in registration with discharge passage 19, is arranged in first radially enlarged section 23 of the discharge passage 19 and moves reciprocally therein in longitudinal direction from a first position to a second position during each discharge stroke of piston 13 and from said second position to said first position during each suction stroke of piston 13, said member being actuated by the pumped fluid. A facia surface 39 on inlet valve member 35 covers the ends of and closes the second passages 29 when member 35 is in the suction position during a discharge stroke of the piston 13 and uncovers the ends of and opens the suction passages 29 when member 35 is in the first position during a suction stroke of the piston 13. An outlet valve member 41, which may be of the poppet valve type, is arranged in second radially enlarged section 25 of discharge passage 19 and moves reciprocally therein in longitudinal direction from a first position to a second position during each discharge stroke of piston 13 and from said second position to said first position during each suction stroke of piston 13 actuated by the pumped fluid. In the embodiment illustrated, outlet valve member 41 is in the form of a cylinder having a chamfered surface 43 at one end. A longitudinal center passage 45 extends part way through the member 41 and connects to a multiplicity of passages 47 extending between passage 45 and the chamfered surface 43. When outlet valve member 41 is in its first position during a suction stroke of piston 13,

bore 19 is closed by one end of the member covering the bore at its point of intersection with second enlarged section 25. When outlet valve member 41 is in its second position during a discharge stroke of piston 13, bore 19 is opened with flow continuity obtaining through the 5 passages 47 and passage 45 in member 41.

In the embodiment shown in the drawing, discharge passage 19, first radially enlarged section 23 of discharge passage 19, second radially enlarged section 25 of discharge passage 19, annular recess 27 and suction passages 29 are defined within valve body portion 17 by an array of core members comprising a thrust block 49, a first follower block 51, a second follower block 53 and a facia block 55, arranged in concentric alignment in a counterbore 57 and a core bore 59 in the valve body portion 17. A bore and counterbore through the center of thrust block 49 define respectively the fluid outlet end of and the second radially enlarged section 25 of discharge passage 19. Milled or otherwise formed recessed peripheral edges on mating faces of thrust block 49 and first follower block 51, together with a portion of wall surface of counterbore 57, define the annular recess 27. Suction passages 29 are drilled or otherwise formed in first follower block 51. First radially enlarged section 23 of discharge passage 19 is defined by a center hole in second follower block 53. Facia block 55 provides an annular bearing surface for inlet valve member 35 in its first or suction position.

All surfaces serving valving functions are flat lapped surfaces, and are prestressed in assembly. O rings 61 are provided in peripheral grooves on the thrust block and first follower block to effect sealing, and weep holes 63 and 65 are provided for seepage draining. The valve body may be affixed to the pump and component prestressing effected by means of stud bolts 67. Connector means such as 69 and 71 may be provided to connect fluid inlet 33 and fluid outlet 21 to inlet and discharge conduits.

In operation, the apparatus of the present invention functions as follows:

Under an assumed inlet line pressure of about 2000 p.s.i.g. and an assumed discharge line pressure of about 40 50,000 p.s.i.g., fluid flows through inlet 33, intake passage 31, annular recess 27, suction passages 29, first radially enlarged section 23 of discharge passage 19 and pump port 15 into a pumping chamber of reciprocating pump 11, during each suction stroke of the piston 13. During a suction stroke, inlet valve member 35 is held in its first position under inlet pressure, permitting fluid flow through the first radially enlarged section 23 of discharge passage 19 from suction passages 29 and outlet valve member 41 is held in its first position under a pressure differential obtaining between the inlet and discharge line pressures, closing discharge passage 19 at its intersection with the interface defined between thrust block 49 and first follower block 51. Upon completion of a suction stroke and the start of a discharge stroke, inlet valve member 35 is moved to its second position by a pressure differential obtaining between the initial discharge pressure and the inlet pressure, closing suction passages 29, and outlet valve member 41 is moved to its second position, opening discharge passage 19. During the discharge stroke, piston 13 forces fluid from the pumping chamber, through pump port 15, first radially enlarged section 23, discharge passage 19, second radially enlarged section 25 and fluid outlet 21 into the discharge line. The above operation is cyclically repeated during continuous operation.

The foregoing disclosure and the drawing will reveal to persons familiar with the art that only three components of the illustrated embodiment of our invention are subjected to cyclic loading, viz, first follower block 51, second follower block 53 and facia block 55. None of these components has a flow surface discontinuity which could become a stress concentration point.

In the light of the foregoing disclosure, it is conceivable that modifications to our invention will occur to persons skilled in the mechanical arts. Accordingly, it is to be

understood that while in the foregoing description, certain specific details have been set forth, variations may be made in these without departing from the spirit of the present invention. The foregoing description is intended to clarify understanding of this invention and no unnecessary limitations should be understood therefrom.

What is claimed is:

1. A fluid intensifier valve adapted for connection to a discharge port of a pump which contains a reciprocating piston, comprising, in combination, a body portion having a discharge passage connecting to said port and extending longitudinally through a multiplicity of core block members disposed interiorly of said body portion to a fluid outlet, a first longitudinally extending radially enlarged section in said discharge passage adjacent said discharge port and thereto connecting, a second longitudinally extending radially enlarged section in said discharge passage, an annular recess interior of the body portion transversely surrounding said discharge passage, longitudinally displaced from said first radially enlarged section of said discharge passage and defined by said core block members and an internal wall of said body portion, a multiplicity of suction passages connecting said annular recess and said first radially enlarged section and an intake passage connecting said annular recess to a fluid inlet at the body portion exterior; an inlet valve member in said first radially enlarged section adapted to move reciprocally in longitudinal direction from a first position to a second position during a discharge stroke of the reciprocating piston and from said second position to said first position during a suction stroke of the reciprocating piston and having an opening extending therethrough in registration with said discharge passage and a surface arranged to close said suction passages when in said second position and to open said suction passages when in said first position; and a discharge valve member in said second radially enlarged section adapted to move reciprocally in longitudinal direction from a first position to a second position during a discharge stroke of the reciprocating piston and from said second position to said first position during a suction stroke of the reciprocating piston, said discharge valve member having means adapted to close the discharge passage when in said first position and to open said discharge passage when in said second position.

2. A fluid intensifier valve adapted for connection to an open ended cylinder which contains a reciprocating piston, comprising, in combination, a body portion having a face adapted for connection to said open ended cylinder, a bore connecting to said open ended cylinder and extending longitudinally through a multiplicity of core block members disposed interiorly of said body portion to a fluid outlet, a first counterbore in one of said core block members adjacent the face, a second counterbore in another of said core block members interior of the body portion, an annular recess arranged coaxially with respect to said bore and defined by said bore block members and an internal wall of said body portion, a multiplicity of radially and longitudinally extending passages connecting said annular recess and said first counterbore, and a radially extending passage connecting said annular recess to a fluid inlet at the body portion exterior; an annular valve disc in said first counterbore adapted to move reciprocally in longitudinal direction from a first position to a second position during a discharge stroke of the reciprocating piston and from the second position to the first position during a suction stroke of the reciprocating piston and having an opening extending therethrough in registration with the bore and an annular surface arranged to close the multiplicity of radially and longitudinally extending passages connecting the annular recess and said first counterbore when in said second position and to open said passages when in said first position; and a poppet valve member in said second counterbore adapted to move reciprocally in longitudinal direction from a first position to a second position during a discharge stroke of the reciprocating piston and from said second position to said

first position during a suction stroke of the reciprocating piston and having a surface arranged to close the bore when in said first position and to open the bore when in said second position.
